UNITED STATES PATENT OFFICE.

JOHN MACLAURIN, OF BROOKFIELD, MASSACHUSETTS.

SEALING-MACHINE.

1,196,797.

Specification of Letters Patent. Patented Sept. 5, 1916.

Application filed July 6, 1915. Serial No. 38,382.

To all whom it may concern:

Be it known that I, JOHN MACLAURIN, a subject of the King of England, residing at Brookfield, in the county of Worcester and State of Massachusetts, have invented certain new and useful Improvements in Sealing-Machines; and I do hereby declare the following to be a full, clear, and exact description of the invention, such as will enable others skilled in the art to which it appertains to make and use the same.

This invention relates to sealing machines and to that class wherein the sealing tape is carried by and forms a part of the machine.

An object of this invention is to provide a sealing machine using a roll of sealing tape in a capacity of a pressure roller.

A further object of this invention is a provision of a sealing machine having a roll of sealing tape to serve as a pressure roller and automatic means for moving the relative position of said roll of sealing tape with respect to said tape as the diameter of said roll decreases.

A further object of this invention is a provision of an improved means for applying the sealing tape in such a manner that the sealing tape is fed from the machine and cut while in dry state.

Further objects will be apparent from the following specification, appended claims and drawings in which—

Figure 1 is an isometric perspective view of a machine of this type showing parts thereof broken away for the sake of clearness, and Fig. 2 is a bottom view of the machine.

As it is necessary to provide an applying roller for a sealing machine, it is apparent that the roll of sealing tape may be used as the applying roller but provision must be made for moving said roll of tape with respect to the frame as the diameter of said roll decreases when said tape is being used.

The mounting and adjustment of a roll of sealing tape with respect to a frame forms the basis of this invention and to provide a complete machine, other details are combined therewith.

Referring to the drawings, there is shown a frame 10 having a handle 11 formed integral therewith, and this frame is recessed as at 12 to receive a swinging frame 13 which is pivotally mounted in the forward end of the frame by having a trunnion 14

formed on each side of the forward end of said frame. This frame supports a shaft 15 to which a roll of sealing tape 16 is rigidly attached in any well known manner and this shaft also supports a ratchet wheel 17 which through co-operation with the pawl 18 restricts the rotation of the shaft 15 and roll of paper 16 to one direction.

The frame 13 has the inside faces of the side members provided with guides 19 in which a yoke 20 is slidably mounted and this yoke supports a pressure roller 21 which is adapted to bear against the roll of tape 16 to control the unwinding of the tape for application. The yoke 20 is normally advanced to cause the roller 21 to engage with the roll 16 by a compression spring 22 coiled about a stem 23 which extends from the yoke 20 through a portion of the frame 13.

The rear cross piece 24 of the frame 13 has a spur 25 formed thereon and this spur engages one or another of the notches formed in the rack 26. This rack is pivoted as at 27 to the frame and has a rearwardly extending arm 28 against which a compression spring 29 bears. The compression spring 29 has sufficient strength to hold the rack 26 in engagement with the frame 13 to prevent movement of said frame when the machine is lifted or moved from place to place. When sufficient paper has been unwound from the roll 16 to materially reduce its diameter, rollers 30 engage the paper and the lever 31 which supports the rollers 30 is swung on its fulcrum 32 to cause the rack 33 pivotally carried by said lever to have one of its notches engage the spur 25 and thereby swing the frame 13 downwardly to cause the succeeding notch of the rack 26 to receive the spur 25. The rack 33 is normally held in engagement with the spur 25 as by a spring 34, and after the lever 31 has been swung to swing the frame, it is returned to a normal position as by a spring 35. The frame 10 may be recessed as at 36 to receive the rollers 30.

As the tape is unwound from the roll 16 and pressure roller 21, the tape passes over a cross bar 37 from where it passes through the slot 38 where it is delivered upon the wrapper of a package. When sufficient tape has been fed upon the wrapper, the end is severed as by a cutter 39 actuated by the arm 40 connected to the rock shaft 41 to which a handle 42 is attached. The handle 42 rises to a convenient location with re-

spect to the handle 11 so that an operator may manipulate a cutter without removing his hand from the sealing machine.

The surface upon which the tape is fed is moistened by a film of liquid supplied by the felt covering 43 over the perforated bottom member 44 of a container 45 which has its side walls provided with guides 46 for slideable engagement with a recessed portion of the frame 10.

It is thought that the operation of this device is evident in view of the foregoing and that further description thereof is unnecessary. Also, it is apparent that various modifications may be had within the scope of this invention, so that drawings submitted herewith are for illustrative purposes only.

Having thus described my invention, I claim:

1. In a sealing machine, an applying roller comprising a roll of tape to be applied, said roller being rotatably mounted for rotation in one direction and means for varying the relation of the mounting of said roller as the tape comprising said roller is consumed.

2. In a sealing machine, a frame, an applying roller movably journaled therein, said applying roller comprising a roll of sealing tape which in use becomes of smaller diameters and means for automatically moving said applying roller with respect to said frame.

3. In a sealing machine, a frame, a supplemental frame pivoted therein, an applying

roller journaled in said supplemental frame, said applying roller comprising a roll of sealing tape of which the diameter decreases as the sealing tape comprising this roll is consumed, a pressure roller movably carried by said supplemental frame for engagement with said applying roller, and means for moving said supplemental frame with respect to said frame.

4. In a sealing machine, a frame, a supplemental frame pivoted therein, an applying roller journaled in said supplemental frame, a pressure roller slidably carried by said supplemental frame, a rack carried by said frame for normally holding said supplemental frame in a relatively fixed position, a supplemental rack movably carried by said frame for imparting motion to said supplemental frame and means for imparting motion to said moving rack.

5. In a sealing machine, a frame, a supplemental frame pivoted therein, an applying roller journaled in said supplemental frame, a pressure roller slidably carried in said supplemental frame, said applying roller comprising a roll of sealing tape which becomes of reduced diameter as said tape is used, a cutter for severing the tape when desired and a moistener for applying a film of moisture to said sealing tape.

In testimony whereof I affix my signature in presence of two witnesses,

JOHN MacLAURIN.
